DESIGN FOR A BRACELET

Cecil F. Carter, New York, N. Y.

Application February 14, 1946, Serial No. 126,551

Term of patent 7 years

(Cl. D45—4)

To all whom it may concern:

Be it known that I, Cecil F. Carter, a citizen of the United States, residing at New York, in the county and State of New York, have invented a new, original, and ornamental Design for a Bracelet, of which the following is a specification, reference being had to the accompanying drawing, forming part thereof.

Fig. 1 is a plan view of a bracelet embodying my new design;

Fig. 2 is a side elevation of the same; and

Fig. 3 is an end view of the bracelet.

I claim:

The ornamental design for a bracelet, substantially as shown.

CECIL F. CARTER.
